T. A. REYNOLDS

SUCKER ROD WRENCH

Filed March 16, 1927

INVENTOR;
Thomas A. Reynolds
By Martin P. Smith Atty.

UNITED STATES PATENT OFFICE.

THOMAS A. REYNOLDS, OF LOS ANGELES, CALIFORNIA.

SUCKER-ROD WRENCH.

Application filed March 16, 1927. Serial No. 175,880.

My invention relates to a wrench that is particularly designed for use in "breaking" or disengaging pump or sucker rods that are utilized in the operation of deep well pumps, 5 the principal objects of my invention being to provide a wrench that is relatively simple in construction, inexpensive of manufacture and capable of being easily and quickly applied to or removed from a sucker rod or 10 the like.

Further objects of my invention are to provide a wrench of the character referred to that has a one-piece jaw that is adapted to engage the squared portion of a sucker 15 rod and which jaw has pivotally connected thereto, a handle that may be swung a short distance in either direction while breaking or disengaging a sucker rod, thereby enabling an increased degree of leverage to be 20 applied to the wrench in the rod connecting and disconnecting operations.

With the foregoing and other objects in view, my invention consists in certain novel features of construction and arrangement 25 of parts that will hereinafter be more fully described and claimed and illustrated in the accompanying drawing, in which—

Fig. 1 is a perspective view of a sucker rod wrench constructed in accordance with 30 my invention.

Fig. 2 is a vertical section taken on the line 2—2 of Fig. 1.

Fig. 3 is a section taken on the line 3—3 of Fig. 2.

Referring by numerals to the accompanying drawings, which illustrate a practical embodiment of my invention, 10 designates a substantially U-shaped jaw having a relatively short leg 11 and a longer leg 12 and 15 the substantially rectangular space 13 between said legs is of such size as to readily receive the square or non-circular portion of a sucker rod section and which square or non-circular portion, it will be understood, is formed on the rod adjacent to each 20 end.

The end of the short leg 11 of the jaw is preferably provided with an inwardly beveled end 14 that facilitates the entrance 25 of the rod into the space 13 within the jaw and formed integral with the outer end of the longer leg of jaw 11, is an arcuate plate 15 in which is formed a curved slot 16.

Screw-seated in arm 12 a short distance 30 inwardly from slot 16, is the threaded portion 17 of a bolt, the same having an en-

larged body portion 18 that projects outwardly or upwardly from the face of leg 12 and this enlarged body portion of the bolt serves as a trunnion or axis for the 60 wrench handle 19. This wrench handle is in the form of a bar, the greater portion of which is rounded in order to be readily grasped in the hands and the end that is pivotally mounted on the bolt or trunnion 18, is retained thereon by the head 20 of 65 said bolt.

A shoulder 21 is formed between the body 18 of the bolt and the threaded portion 17 thereof, said shoulder bearing directly 70 against the face of the leg 12 of the jaw and the bolt is locked to the leg 12 by means of a counterpin 22 that passes through that portion of the bolt that projects through 75 leg 12.

Arcuate slot 16 is concentric with the axis of the bolt to which the handle is pivotally connected and I prefer to form the plate 15 so that the same and the arcuate slot 16 extend outwardly from the leg 12 opposite 80 from the side on which the rod receiving notch or opening 13 is formed and thus the handle 19 has a greater swinging movement outwardly from the jaw 10 than toward the side of the jaw in which the opening 13 is 85 formed.

Formed integral with or fixed to the handle 19, is a pin 23 that projects through the arcuate slot 16 and formed integral with the end of this pin is a head 24. The width of this head is practically equal to the diameter of pin 23, but said head having greater length than the diameter of the pin, and said head is arranged so that its length lies parallel with the axis of handle 19. 95

Thus when the handle and jaw of the wrench are properly assembled, the head 24 of pin 23 lies across or at right angles to the length of slot 16 and in order to assemble the jaw and the handle, the parts must be turned so that head 24 may be inserted through slot 16 and which operation must necessarily take place before the end of the handle is pivoted to the end jaw by bolt 18.

In the use of my improved wrench, the jaw 10 is manipulated so that the square portion of the sucker rod is positioned in the opening 13 and by swinging the handle 19 with a quick movement so that pin 23 strikes against the end of the arcuate slot 16, a blow of considerable force may be impressed on the end of the longer leg 12 of 110

the jaw and which blow is of material assistance in starting the breaking or unscrewing of the joint or the tightening up of the joint at the finish of the coupling operations. In other words, by pivotally mounting the handle on the jaw, the latter may be "hammered" by proper manipulation of the handle and which action is very effective in breaking the joint loose at the beginning 10 of the coupling operations and likewise for tightening the joint at the termination of the coupling operation.

A sucker rod wrench of my improved construction is comparatively simple, may be 15 easily and cheaply produced, is of strong substantial structure and is very effective in performing the functions for which it is intended.

It will be understood that minor changes 20 in the size, form and construction of the

various parts of my improved sucker rod wrench may be made and substituted for those herein shown and described without departing from the spirit of my invention, the scope of which is set forth in the appended claim. 25

I claim as my invention:

In a sucker rod wrench, a substantially U-shaped integral jaw having a non-circular opening for the reception of a sucker rod, 30 a handle pivotally connected to one of the legs of said jaw and a pin and slot connection between said jaw and handle, said slot being concentrically arranged relative to the axis of pivotal connection between said jaw 35 and handle.

In testimony whereof I affix my signature.

THOMAS A. REYNOLDS.
